ATTORNEY

UNITED STATES PATENT OFFICE.

JOHN D. BOYLE, OF PELHAM MANOR, NEW YORK.

POWDER PACKAGE.

Application filed June 26, 1922. Serial No. 570,985.

To all whom it may concern:

Be it known that I, JOHN D. BOYLE, a subject of the King of Great Britain, and a resident of Pelham Manor, county of West-
5 chester, and State of New York, have invented certain new and useful Improvements in Powder Packages, of which the following is a specification.

This invention relates to the packaging
10 and dispensing of pulverulent material such as toilet powders.

Some of the more important objects of
15 the invention are to provide an original form of package which will be neat and attractive in appearance, simple and inexpensive to manufacture and which will have incorporated within it practical and effective means for dispensing the powder in a specified quantity, and regardless of the position
20 in which the box is held.

Other objects and the various novel features which make the attainment of such objects possible, will appear as the specification proceeds.

25 In the drawing accompanying and forming part of this specification I have illustrated but two of the many possible forms the invention may take and therefore wish it understood that the structure may be
30 modified and changed in various respects without departure from the true spirit and scope of the invention.

Figure 1 in the drawing referred to is a perspective view of the package embodied
35 in pyramidal form and illustrating the method of its use.

Figure 2 is a broken front view of the package, partly in section.

40 Figure 3 is a substantially central vertical sectional view of the same.

Figure 4 is a horizontal section on substantially the plane of line 4—4 of Figure 2.

Figure 5 is a central sectional view of a
45 form of the invention in which the container is of cylindrical shape.

In a preferred form of the invention the container is of substantially pyramidal shape having a flat rectangular bottom 5 from which rise the front and back sides 6,
50 7 and the narrower ends 8, 9, converging to a point having a discharge opening 10.

The sides 6, 7 are flexible and elastic so
55 that they may be compressed or pinched together, as indicated in Figure 1, and the ends 8, 9 are relatively rigid and stiff to brace the compressible sides and limit the ex-

tent of their compression. These results may be effected by making the box of relatively stiff cardboard, the wider expanse of the sides providing sufficient flexibility for
60 the compression movements and the smaller expanse of the ends providing the stiffness and rigidity necessary for bracing the sides and limiting the compressive movements.
65 The folding of the cardboard at the bottom to close the box provides the rigidity and strength for holding the sides and ends rigidly connected and also forms a relatively broad flat supporting base for the
70 package.

The powder is discharged from the box in the form of puffs or clouds by means of a tube 11 secured in the mouth of the outlet and extending down through the body of the powder to a point close to the bottom
75 of the box. This tube in a preferred form of the invention is made of paper coiled or rolled into tubular shape, as indicated, and impregnated or coated with wax or like material to make it smooth and impervious.
80 This prevents the powder from adhering to the tube and causes it to discharge smoothly and evenly with but a slight pressure on the sides of the box.

This discharge tube, as in my former patent, may have an enlargement or collecting funnel at the lower end of the same, such as I have indicated at 12, by somewhat enlarging the end of the tube, or as shown at 13, a flap may be extended from
90 one of the sides of the box and folded back thereinto to provide a collection chamber or funnel 14 about the end of the tube. This flap is indicated as being simply bent up into the body of the container and as having an extension 15 projecting at an angle
95 downwardly from the innermost portion of the flap to the bottom of the box, the lower end of the tube being shown as fitting in a slot 16 formed at the junction of this return flap with the main body portion of the flap.

The powder can enter this pocket or collecting chamber by a slot 17 provided in the flap 13 and also by way of the slot 16 which is provided for the reception of the lower end of the tube. The discharge tube is usually secured in the mouth of the outlet by forcing the tube thereinto until it flattens out and conforms more or less to the rectangular cross section of the box at this point, substantially as indicated at 18. An
105
110

adhesive or holding agent may be employed to permanently secure the thus conformed end of the tube in place, as indicated at 19.

The discharge tube is usually inserted

- 5 while the box is held in inverted relation and the bottom of the box is open. After the tube is secured in place the box is charged with powder and the flap which provides the collecting chamber is forced
- 10 inward and about the lower end of the tube, after which the bottom flaps are closed. A wrapper 20 may then be applied about the box to seal the bottom air-tight, and to close off the outlet in the peak of the box. This
- 15 provides an air-tight container protecting the contents from moisture and preventing the loss of fragrance or other qualities. The contents is available at any time upon simply clipping the tip of the wrapper to uncover
- 20 the end of the discharge tube and then by squeezing the sides of the box the material may be ejected in cloud-like form upwardly, downwardly or in any direction. The substantially rigid end walls brace the flexible
- 25 side walls and operate in effect to limit the amount of compressive force which can be applied thereto. By limiting the pressure which can be applied only a proper amount of powder will be expelled.
- 30 In the form of the device disclosed in Figure 5 the container 21 is of cylindrical form, the side walls thereof being sufficiently elastic to provide the necessary pumping action, and the top and bottom being sufficiently rigid to limit the pumping action.
- 35 The discharge tube in this case is shown as centered in the top of the box, being held therein by suitable adhesive, as before, and having its mouth sealed by a paster or wrap-
- 40 per 22.

In addition to its simplicity and cheapness both forms of this improved package

have the advantage that the boxes can be made up, filled, weighed and sealed on more or less automatic and standard machines.

45

What I claim is:

1. An original powder package comprising a substantially pyramidal container of relatively stiff but flexible springy material having a rigid flat bottom for supporting the package upright, substantially rigid end walls and compressible side walls tapering to the peak of the pyramid, the substantially rigid end walls bracing and limiting the compressive movements of the side walls, the container thus constructed having a discharge throat in the peak of the same, a discharge tube extending from near the bottom of the container and having its upper end secured in the discharge throat, a flap in the bottom of the container bent up about the lower end of the discharge tube.

2. The structure of claim 1 in which the tube is of waxed paper to reduce friction and facilitate free, smooth discharge of the 65

contents.

3. An original powder package comprising a container having slightly compressible side walls rigidly braced to prevent collapse or buckling of the container, a discharge tube of smooth moisture-proof waxed paper extending from near the bottom of the container through the top thereof.

4. In a powder package, a container having slightly compressible side walls rigidly braced apart by end walls, a discharge tube extending from near the bottom of the container to the top thereof and a flap in the bottom of the container bent to form a funnel or collection chamber about the lower 80 end of the tube.

In witness whereof, I have hereunto set my hand this 22nd day of June, 1922.

JOHN D. BOYLE.
